C. WHITE

CARRIER WAVE SIGNALING SYSTEM

Filed Dec. 21, 1920

Inventor:
Charles White

by C. L. Sprague, Atty.

UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

CARRIER-WAVE SIGNALING SYSTEM.

Application filed December 21, 1920. Serial No. 432,191.

To all whom it may concern:

Be it known that I, CHARLES WHITE, a citizen of the United States, residing at East Orange, in the county of Essex, State 5 of New Jersey, have invented certain new and useful Improvements in Carrier-Wave Signaling Systems, of which the following is a full, clear, concise, and exact description.

10 This invention relates to carrier wave signaling systems and more particularly to systems of multiplex telephony employing carrier waves wherein carrier waves of distinctive frequencies are used for transmissions 15 in opposite directions, and wherein such carrier waves are normally impressed upon the transmission medium. Such medium may comprise any of the natural media employed in radio transmission or a conductive transmission line of any kind.

Call signaling systems of this general type are known wherein the removal of the carrier wave from the transmission medium actuates a signaling device at the called 25 station. Such systems may be defective however in the fact that any accidental removal of the carrier wave from the medium will cause the actuation of the signaling device and so give rise to a false signal indication.

30 The object of this invention is to provide an organization of elements in a system of this general type, wherein such defect will be overcome. Another object of the invention is to provide a call signaling system 35 wherein the signaling device will be actuated only when the carrier is removed from the transmission medium in a predetermined manner. Still another object is to provide a system of this kind which is not affected by foreign currents which may find their way 40 into the system. A still further object is to provide a system which will accomplish the above results and still be simple in construction and operation.

45 These objects are accomplished in the present invention, by providing means for removing the carrier wave from the transmission medium periodically at a predetermined rate and means at the called station 50 for actuating a signaling device only in response to such removal at such predeter-

mined rate. At a carrier wave transmitting station a relay may be actuated in response to ordinary low frequency ringing current incoming from a calling station to intermittently short-circuit the carrier wave supply to a transmission line. At a cooperating receiving station a second relay may be actuated at each interruption of the carrier wave. A third relay controlled thereby and responsive only to such periodic actuation may cause a signal indication at a called station.

Proceeding now to a detailed description of the invention with reference to the accompanying drawing, Fig. 1 shows one embodiment thereof. Fig. 2 shows a detail of the system of Fig. 1. It is to be understood that other organizations of elements may be employed in the working of the invention.

In Fig. 1 there is shown, a two-way channel 1 of a carrier wave terminal station with its accompanying signaling apparatus and low frequency terminal line 3, and a second low frequency line 2 connected through 75 suitable means to a common transmission line ML. For the purpose of description one terminal station only of the system is shown. It is to be understood that a similar cooperating station is connected to the distant end 80 of the common line ML.

The low frequency line 2, terminating at one end in a station B is connected to the common line ML through a low-pass filter LP. This filter is of a type described in 85 patent No. 1,227,113 issued on May 22, 1917 to G. A. Campbell. It will be referred to hereinafter as a low-pass filter since it is designed to pass without appreciable attenuation currents of all frequencies below and 90 including the highest essential frequency of the voice range, and practically to extinguish currents of higher frequencies.

A carrier current terminal station is also connected to the common line ML through a 95 high-pass filter HP. This filter is also of a type described in the Campbell patent mentioned above and hereinafter will be spoken of as a high-pass filter, since it is designed to pass without appreciable attenuation all currents having frequencies higher than the highest essential frequency of the 100

voice range, and to suppress all currents of frequencies within the essential voice range and below.

Connected to the two-way channel 1 of the carrier terminal station is a low frequency line 3 terminating at the distant end in a low frequency station A.

Low frequency stations A and B, may be subscribers' stations or, as is more common, 10 they may be ordinary telephone exchanges. The station A, furthermore, may be located in the same building with the carrier apparatus or it may be located at a distance therefrom.

15 The low frequency line 3, at the carrier terminal station 1, extends through the normally closed contacts of relay 4, the function of which will be described hereinafter, to the line terminals of a balanced transformer 5. A low frequency network LFN, connected to the opposite terminals of the balanced transformer 5 is provided to balance the low frequency line 3 in a well-known manner. The series winding of the 20 hybrid coil 5 is connected to the voice frequency input circuit of a modulator M. An oscillator O is also connected to the carrier current input circuit of the modulator M. The output circuit of modulator M is connected to a band filter MBF¹. This filter is adapted to pass a broad band of frequencies without substantial attenuation, while practically suppressing all frequencies outside of such band both above and below. 25 This filter is also of the general type described in the Campbell patent mentioned above. Connected in series with the band filter MBF¹, are band filters MBF² and MBF³ and one winding of transformer 6. 30 The other winding of transformer 6 is connected across the bridge terminals of a high frequency balanced transformer 7. The line terminals of this coil are connected to the common line ML through the high pass filter HP. Connected to the opposite terminals is a high frequency balancing network HFN. The circuit just described as extending 35 between the balanced transformer 5 and the high frequency balanced transformer 7, comprises the transmitting channel 8 of the two-way carrier channel 1.

A corresponding receiving channel 9 of the two-way channel 1 comprises the series winding of the balanced transformer 7, detector band filter DBF¹ connected in series with band filters DBF² and DBF³, a voice frequency detector D, a receiving amplifier RA and a low pass filter LPF. This filter is similar to the low pass filter LP connected 40 in the low frequency line 2.

The apparatus just described is used primarily for speech transmission. For signaling purposes, an alternating current relay 10 is connected through a condenser 11 and normally closed lower armature and

contact of relay 13 across the low frequency line 3 at a point between the normally closed contacts of relay 4 and the balanced transformer 5. By means of this relay 10 the output circuit of the oscillator O may be short-circuited for purposes hereinafter to be described. The slow release relay 13 is provided to guard the system against false operation. Its normally open upper contact controls a short circuit across the low frequency modulator input circuit, while its normally closed lower contact controls the continuity of the energizing circuit of relay 10.

Connected to the receiving circuit 9 between the receiving amplifier RA and the low pass filter LPF and in shunt therewith is a signal detecting circuit. This circuit comprises a high pass filter HPF, a signal detector SD, a relay 14, a condenser 15 and a battery 16. The high pass filter HPF may be of the same type as the high pass filter HP. The signal detector SD may be of the well-known three electrode thermionic vacuum tube type, which is adapted to translate alternating current of carrier wave frequency into uni-directional current for the operation of relay 14. The battery 16 provides the energy for the operation of relay 14, while the condenser 15 is connected across the windings of relay 14 to improve the operation in a well-known manner. Relay 14 controls the energizing circuit of a relay 17. In either the actuated or un-actuated position of relay 14 a circuit is closed from ground to ground through a battery 18, the winding of relay 17 and one or the other of the contacts of relay 14.

Relay 14 is a two-position relay. The term "two-position relay" as used in this specification means a relay having at least two contact closures whereby two identical or equivalent circuits may be completed therethrough under different energization conditions of the relay. For example, the energizing circuit of relay 17 is closed by the closure of either the front or back contacts of relay 14, therefore, relay 14 is termed "a two-position relay."

Relay 17 through its normally open contact controls a signal lamp 19, the signaling relay 4, and the guarding relay 13. Lamp 19, relay 4 and relay 13 are energized by current from batteries 20, 21, and 22 respectively.

Relay 4 controls the application of ringing current to the low frequency line 3 through its normally open front contacts from the source of ringing current 23.

A thermionic discharge device suitable for use as a signal detector is shown in Fig. 2. The lettered terminals of the arrangement of Fig. 2 are connected to the correspondingly lettered terminals of Fig. 1. The device of Fig. 2 operates in well-known man-

ner, but for further description reference may be had to an article by Messrs. Colpitts and Blackwell on "Carrier current telephony and telegraphy" published in the Journal of the American Institute of Electrical Engineers for April, May and June 1921.

The operation of the system for call signaling will now be described.

Let it be assumed that a party at station A desires to get the attention of a party at a cooperating station at the distant end of the common line ML. By the usual ringing apparatus at such a station, ringing current will be impressed upon line 3 and, flowing through the normally closed contacts of relay 4, normally closed contact of relay 13, winding of relay 10 and the condenser 11, will actuate relay 10 periodically at a rate determined by the frequency of the ringing circuit. Such operation of relay 10 will intermittently short-circuit the output of the oscillator O by intermittently closing a short-circuit at the normally open contact of relay 10. The effect of this will be to intermittently remove the carrier waves at the same rate from the common line ML. It is, of course, understood that carrier waves of distinctive frequency are normally impressed upon the common line ML through the modulator M, the transmitting modulator band filter MBF¹, the end-sections of modulator band filters MBF² and MBF³, the transformer 6, the balanced transformer 7, and the high pass filter HP.

Referring now to receiving channel 9 which for purposes of description will be considered as the cooperating distant station, the normally transmitted carrier waves will be normally received from the common line ML through the high pass filter HP, the balanced transformer 7, the end sections of detector band filters DBF³ and DBF², detector band filter DBF¹, detector D, receiving amplifier RA, and high pass filter HPF, by the signal detector SD. The high frequency carrier wave is translated by the signal detector SD into uni-directional current, to cause the actuation of relay 14. The interruption of the carrier wave at the transmitting station by interrupting the flow of energy to the winding of relay 14 allows its armature to retract against its back contact. Relay 17 is so designed that a single change of position of the armature of relay 14 will not permit sufficient de-energization of relay 17 to allow its armature to retract. On the other hand, the design of relay 17 is such that when the armature of relay 14 vibrates between its front and back contacts at a rate corresponding to the intermittent interruption of the carrier wave at the transmitting station, relay 17 will be deenergized. In order now to again energize relay 17, the armature relay

14 must remain quiescent in either its actuated or unactuated position for a relatively long period of time. In other words, relay 17 is relatively quick to release but slow to operate.

When relay 17 releases, its normally open contact is closed, signal lamp 19 being lighted and relays 4 and 13 being energized thereby. The circuit for lamp 19 extends from ground, through battery 20, lamp 19, closed contact of relay 17 to the ground side of battery 18. The energizing circuit of relay 4 extends from ground, through battery 21, winding of relay 4, closed contact of relay 17, to the ground side of battery 18. The energizing circuit of relay 13 extends from ground, through battery 22, winding of relay 13, closed contact of relay 17, and the ground side of battery 18.

The lighting of lamp 19 provides a signal at the carrier terminal station to indicate that the distant cooperating station is calling. Relay 13 which is quick to operate opens the energizing circuit of relay 10 at its own normally closed lower back contact (now open) and so prevents the party at station A from originating a call. At the same time, the operation of relay 13 short circuits the low frequency input circuit of the modulator M at its normally open upper front contact (now closed). Relay 13 is designed to operate quickly in order that these functions may be performed before the slow-operating relay 4 has caused ringing current from the source 23 to be impressed upon line 3 through its front contacts (now closed). It is necessary to short-circuit the low frequency input circuit of modulator M at this time to prevent singing, since the normally balanced transformer 5 becomes unbalanced when the low frequency line 3 is removed by the operation of relay 4. The impression of ringing current on the line 3 from the source 23 operates a signaling device at station A to attract the attention of the called party.

It should be noted that the same carrier frequency is employed by the calling station for transmission, as is used by the cooperating receiving station for reception. It should be further noted that carrier waves of distinctive frequencies are used at each two-way channel for transmissions in opposite directions and that carrier waves of distinctive frequencies are used for transmission through the several channels of the same station. In some cases the distinctive frequencies of the carrier waves used for transmission by the several channels may be grouped together in a continuous frequency range and the distinctive frequencies used for reception may likewise be grouped together though in a different continuous frequency range. In other cases the distinctive frequencies used for transmission may al-

ternate with the distinctive frequencies used for reception and may extend over the whole frequency range.

In the drawing, the complete circuit of one channel only is shown while two additional channels are merely indicated. It is to be understood that the system is not to be limited to any particular number of channels but that any number of additional channels may be added as the requirements of the case may demand.

It is, of course, understood that the invention is not limited by this particular arrangement of elements but is to be limited only by the scope of the appended claims.

What is claimed is:

1. A method of signaling in a carrier wave signaling system employing a two-position relay, a controlled element and a second relay for controlling said element, which method comprises receiving impulses of carrier waves at a predetermined impulse periodicity, actuating the controlled element only when the two-positioned relay is changing from one position to the other and vice versa at a predetermined rate, and energizing the second relay to prevent actuation of the controlled element when the first relay remains in either position for a duration of time exceeding a definite minimum period.

2. In a signaling system, a transmission medium, means to impress carrier waves on said medium, means to periodically withdraw said waves from said medium at a predetermined rate, a two-positioned relay maintained in one of its positions by the incoming carrier wave and in the other position when the carrier wave is withdrawn, a second relay energized when said first mentioned relay remains in either of its two positions during a period of time longer than that due to the predetermined rate of withdrawal of the carrier waves, and a signaling device controlled by said second relay.

3. In a signaling system, a transmission medium, means to impress carrier waves on said medium, means to periodically withdraw said waves from said medium at a predetermined rate, a two-position relay maintained in one of its positions by the incoming carrier wave and in the other position when the carrier wave is withdrawn, a second relay energized when said first mentioned relay remains in either of its two positions during a period of time longer than that due to the predetermined rate of withdrawal of the carrier waves, and de-energized when said first mentioned relay is alternating between its two positions in synchronism with the withdrawal of the carrier wave and a signaling device controlled by said second relay.

4. A call signal receiving system comprising a thermionic device adapted to trans-

rectional current, a relay connected to said thermionic device and adapted to be normally energized by unidirectional current therefrom, a second relay, an energizing circuit for said second relay, the continuity of which is completed by said first mentioned relay when in either its energized or de-energized condition and interrupted during the period of change from the energized to the deenergized condition and vice versa, and a signaling device controlled by said second mentioned relay.

5. A call signal receiving system comprising a thermionic device adapted to translate high frequency oscillations into unidirectional current, a relay connected to said thermionic device and adapted to be normally energized by unidirectional current therefrom but responding to interruptions of said oscillations at a predetermined rate to change the position of its armature, a second relay, an energizing circuit for said second relay the continuity of which is interrupted by the response of said first mentioned relay to the interruption of said oscillations at said predetermined rate and a signal controlled by said second mentioned relay.

6. In a call signaling system, a transmission medium, means to impress a carrier wave on said medium, means to periodically withdraw said wave from said medium at a predetermined rate, a receiving station, a signal at said receiving station, a two position relay maintained in one position by the received carrier wave and in the other when the carrier wave is withdrawn, a second relay adapted to cause an indication by said signal when said first mentioned relay is changing position at the predetermined rate of interruption of said carrier wave and to prevent such indication when said first mentioned relay remains in either of its positions longer than a predetermined period corresponding to said predetermined rate.

7. In a carrier wave call signaling system, a plurality of speech transmission channels, carrier waves of distinctive frequencies normally impressed upon each channel, means to intermittently withdraw any of said waves from their corresponding channels at a predetermined rate, a two-position relay for each channel, each of said relays being maintained in one of its positions by the carrier wave of distinctive frequency assigned to that channel and in the other position when said carrier wave is withdrawn, a second relay for each channel energized when said first mentioned relay remains in either of its two positions during a period of time longer than that due to the predetermined rate of withdrawal of the carrier waves, and a signaling device for each channel controlled by said second relay.

8. In a carrier wave call signaling system,

- a plurality of speech transmission channels, carrier waves of distinctive frequencies normally impressed upon each channel, means to intermittently withdraw any of said waves 5 from their corresponding channels at a pre-determined rate, a two-position relay for each channel, each maintained in one of its positions by the carrier wave of distinctive frequency assigned to that channel and in the 10 other position when said carrier wave is withdrawn, a second relay, means to energize said second relay when said first mentioned relay is changing its position in synchronism with the withdrawal of the carrier wave and a signaling device controlled 15 by said second relay.
9. A signaling system comprising a line,
- means for applying periodic impulses of alternating current thereto, a relay responsive to said impulses, a controlled element, and a slow-operating quick-releasing relay controlled by the first relay and controlling said element. 20
10. A signaling system comprising a transmission medium, means for impressing periodic impulses of alternating current thereon, a relay responsive to said impulses, a controlled element, and a slow-operating quick-releasing relay controlled by the first relay and controlling said element. 25

In witness whereof, I hereunto subscribe my name this 17th day of December, A. D., 30 1920.

CHARLES WHITE.
